ELECTRICAL DISCHARGE RELAY

Samuel Ruben, New Rochelle, N. Y.

Application September 3, 1932, Serial No. 631,655

2 Claims. (Cl. 250—27.5)

This invention relates to an electrical discharge relay device, and more particularly it relates to a relay device employing in a closed envelope the conductivity of an ionized path of mercury vapor to conduct current between a thermionic cathode and its cooperating anode. An object of the invention is to provide an electrical relay that is controllable within definite voltage values and is capable of conducting a relatively large current into its output circuit.

Broadly, the invention comprises an arrangement of a plurality of thermionic assemblies or triodes with means for preventing the discharge from one unit to another through a metal vapor atmosphere, with means for maintaining a pure electronic discharge in one triode, as contrasted with an ionic discharge in the other triode. The arrangement of elements is similar to that described in my Re-Issue Letters Patent 18,367, by which one of the triodes directly controls the operation of the other through the direct connection between the cathode electrode of the control triode with the control electrode of the output triode. By the terms of the present invention one triode operates by an electronic discharge while the other functions by an ionic discharge through a metal, preferably mercury vapor.

The input or control set of elements is operated at a potential below the ionization potential of the mercury or other metal vapor employed, and the output triode operates above the ionization potential of that vapor.

In devices of this general type in the prior art using a mercury vapor discharge, it is necessary to use in conjunction with it the equivalent of an electron discharge type of tube for the control of the vapor tube, because of operating difficulties based upon inherent factors in the performance of those tubes, such as grid currents and temperature effects.

By the terms of this invention only one tube is required and that has a high amplification efficiency brought about by connecting the elements as described in my said Letters Patent bearing Re-Issue Number 18,367, and my co-pending applications bearing Serial Numbers 553,052 and 580,020, filed respectively July 25, 1931 and December 10, 1931, that is, by connection of the cathode electrode of the control triode with the control electrode of the output triode, the cathode electrodes being insulated from each other and the anode electrodes having different potentials.

Fundamentally, in this tube the control set of

elements is operated at a potential below the ionization potential of the metal to be vaporized, so that there is only an electron control. The output set of elements is directly controlled by the other set, which latter is operated at a potential above the ionization potential of mercury which permits large currents to be discharged through the tube.

To prevent cross current discharge between the active elements of the two triodes, the cathode and grid of each triode are enclosed within an anode element having narrow gaps through which the conductive electrodes and their supports pass, the gap constituting a de-ionization space, by reason of the maintenance thereof of transverse electrical fields of a potential gradient higher than that between the active emission surface of the cathode electrode and its cooperating anode electrode as described in my co-pending application bearing Serial Number 582,714 filed December 23, 1931. The deionization of any ionized mercury or other metal vapor tending to spread beyond the active area about the cathode is accomplished by an electrical field maintained transversely to any leakage discharge beyond that area, the potential therefor being that derived from the normal drop of potential within the tube.

Because of the close spacing between the uncoated part of the cathode extending through the gap portion of the anode, and the adjacent anode wall, there is an electrical field of a potential gradient higher than that between the active emission cathode surface and the anode. The equivalent of such close spacing may be obtained by extending the normal walls of the anode to a sufficient distance beyond the cathode emission surface.

I have found that such a field completely deionizes any ionized metal vapor tending to discharge in a path other than that across the immediate space between the emission coated cathode area and the adjacent anode surface. Without this de-ionizing means the entire tube is filled with a green glow when discharges occur between the several parts. In contrast, because of the de-ionizing structure of my device, no positive ionization is visible except from a view immediately down upon the space between the oxide coated cathode and the adjacent anode wall.

While the preferred method is to utilize a transverse field for de-ionizing any vapor outside of the direct path between coated cathode and anode, in some cases this may be done mechani-

cally, as by the use upon the anode ends of a ceramic disc, such as magnesium oxide, with openings therethrough for the supporting leads. And while mercury vapor is preferred for use in this device, an amalgam of mercury and such alkaline metals as caesium, rubidium and sodium may be employed.

To more completely describe this invention reference is made to the accompanying figures, 10 in which Fig. 1 diagrammatically illustrates a tube constructed in accordance with the terms of my invention and Fig. 2 is illustrative of an electrical circuit in which the tube using a double set of elements, is connected, or, it may be considered 15 that each triode is in a separate vessel, the elements being connected as herein set forth.

Referring more particularly to Fig. 1, 1, 2, 3 and 5 represent respectively the cathode, grid, plate and heater elements of one triode, 1_a, 2_a, 20 3_a and 5_a representing corresponding elements in the other triode. The cathodes are supported by leads 7 and 7_a, the grids by leads 8 and 8_a, and plates by leads 9 and 9_a as mounted by members 10 and 10_a, respectively. To support the various 25 elements glass bead 6 is used, and as a source of mercury vapor an amalgam of mercury-potassium is placed within thin walled vessel 11, which also contains a small quantity of "getter" material, such as magnesium.

Referring more particularly to Fig. 2, in which 30 elements corresponding to those shown in Fig. 1, bear like numbers, in the auxiliary equipment the source of input potential is indicated at L, B being a source of potential for controlling the electron 35 emission between cathode electrode 1 and anode electrode 3. Through transformer T the cathodes are heated by conduction and the load is indicated at R₁, which may be of the resistance or inductive type. In the output set of elements 40 control electrode 2_a is negatively biased by battery B₁ with respect to cathode electrode 1_a, so that under normal conditions there is a negligible ionized mercury discharge between cathode electrode 1_a and anode electrode 3_a. At Z is an impedance in series with the negative bias potential 45 source to control electrode 2_a. At R is a resistance potentiometer device for varying the potential to anode electrode 3; this is connected across the anode electrode current supply shown 50 here as generator G.

It is to be noted that the cathode electrode 1 of the control triode is connected to the control electrode 2_a of the other triode, so that an impedance change between cathode electrode 1 and plate 3, causes a potential change on control electrode 2_a. Thus, if the normal bias of grid 2_a is

such as to prevent the ionic discharge between cathode electrode 1_a and anode electrode 3_a, by decreasing the impedance between cathode electrode 1 and anode electrode 2, as by reducing the negative bias in the control electrode 2, there is a resultant decrease of negative bias on control electrode 2_a, with an attendant large current flow which is characteristic of ionized mercury vapor discharges.

A desirable or essential method of operation 10 which allows the direct control of this tube by such limited current supply sources as photoelectric cells, is to maintain the control anode electrode 2 potential below the ionization potential of mercury vapor as, for example, below ten 15 volts. Thus, in the same device by the combination and connections shown there is a heavy current ionic discharge for operating a mechanism, yet controlled by an electron discharge, allowing a high degree of sensitivity, negligible current 20 consumption and permitting the use of readily replaceable units.

With the elements of the separate triodes properly connected, each triode may be placed within a separate container so that between the 25 elements of the first triode there is an electron discharge, and between the elements of the other, an ionic discharge; there being thus made provision for the prevention of leakage discharge between the triodes.

What I claim is:

1. A relay tube comprising a sealed envelope containing an ionizable medium comprising a mercury amalgam, an electron discharge assembly comprising a cathode, an anode and a control 35 element, an ionic discharge assembly comprising a cathode, an anode and a control element, the cathode of the electron discharge assembly being connected to the control electrode of the 40 ionic discharge assembly, blocking means at the terminals of the ionic discharge assembly for confining the discharge thereof to the space between the cathode and anode.

2. A relay tube comprising a sealed envelope containing an ionizable medium, an electron discharge assembly comprising a cathode, an anode and a control element, an ionic discharge assembly comprising a cathode, an anode and a control element, the cathode of the electron discharge assembly being connected to the control electrode of the 45 ionic discharge assembly, blocking means at the terminals of the ionic discharge assembly for confining the discharge thereof to the space between the cathode and anode.

SAMUEL RUBEN.
